UNITED STATES PATENT OFFICE.

ARNOLD SESSLER, OF NEW YORK, N. Y.

DESIGN FOR A LEGGING.

SPECIFICATION forming part of Design No. 29,691, dated November 15, 1898.

Application filed April 24, 1896. Serial No. 588,977. Term of patent 7 years.

To all whom it may concern:

Be it known that I, ARNOLD SESSLER, a citizen of the United States, residing at New York city, in the county and State of New York, 5 have invented and produced a new and original Design for Open Leggings; and I do hereby declare the following to be a full, clear, and exact description of the same, reference being had to the accompanying drawing, 10 forming a part thereof, in which is shown a perspective view of a legging embodying my design.

My design relates to the new and original external shape or configuration of the opening.

15 The leading features of my design are the body or main part A of the legging, made of the general shape and configuration of the calf and ankle, the bottom edge being provided with a strip B, extending entirely around 20 the same, with the front opening extending

from the top to the bottom and the bottom edge being rounded, the curve thereof merging into the front portion and the front opening having a tongue D behind it. The front edges are provided with strips C, which extend parallel with each other and on which are placed the studs G and through which extend the eyelets H. At the bottom of the legging is a strap E.

Having now described my invention, what I claim, and desire to secure by Letters Patent, is—

The design for a legging, substantially as herein shown and described.

This specification signed and witnessed this 22d day of April, 1896.

ARNOLD SESSLER.
